DOOR LIFTER

Filed March 26, 1929

S. J. Jacobsmeier Inventor

Watson E. Coleman Attorney

UNITED STATES PATENT OFFICE

STEPHEN J. JACOBSMEIER, OF SALEM, IOWA

DOOR LIFTER

Application filed March 26, 1929. Serial No. 350,062.

This invention relates to an improved means for hanging sliding doors, particularly doors of large size like barn or garage doors.

5. The primary object of this invention is to provide a structure for supporting a door from a carrying track whereby the door may be raised or lowered upon the track when the same is desirable to facilitate the shifting thereof.

It frequently occurs that doors of large size sag due to a weakening of the supporting track or the structure upon which the track is mounted, as a result of which the 15 door comes into contact with the ground or surface lying therebeneath, making it difficult to open and shut the door. This condition also frequently results from the settling of the building or it may be that 20 difficulty will be experienced in opening the door in winter weather when snow or ice has formed and frozen about the bottom of the door.

The object of the present invention therefore is to provide a means whereby the door can first be conveniently shifted vertically to free the lower edge thereof from any obstruction and to enable the operator to more readily slide the door to open or closed position.

Another object of the present invention is to provide a structure by means of which the foregoing may be effected, which will be of simple design, but strong and durable, 35 and easy to install.

The invention will be best understood from a consideration of the following detailed description taken in connection with the accompanying drawing forming a part 40 of this specification, with the understanding, however, that the invention is not confined to any strict conformity with the showing of the drawing but may be changed or modified so long as such changes or modifications 45 mark no material departure from the salient

features of the invention as expressed in the appended claims.

In the drawing:—

Figure 1 is a view in elevation of the door structure mounted in accordance with the present invention;

Figure 2 is a sectional view taken upon the line 2—2 of Figure 1.

Referring to the drawing in detail, the numeral 1 indicates a portion of a building, such for example as a barn or garage having a door opening 2 over which is positioned a door 3.

Secured to the face of the building above the door opening in the usual manner is a track rail 4 upon which is mounted a plurality of rollers each of which is enclosed in a casing 6 which has a top 6^a and inner and outer sides 6^b and 6^c respectively. The outer side 6^c of the casing extends to a point adjacent the lower side of the track 4 as shown in Figure 2 for the purpose hereinafter described. As shown, only the lower edge of the casing 6 is open so as to permit contact of the wheels therein with the track rail 4.

In the present invention the outer wall 6^c of each casing has secured thereto and extending outwardly and downwardly therefrom, the brace bar 7, the lower end of which overlies and bears against the outer face of the door 3 in the manner shown in Figure 2.

As shown in Figure 2, the portion of the brace bar 7 between the upper end where it is secured to the wall 6^c of the roller casing and the lower end which engages the door 3 is offset with respect to the outer wall of the roller casing and the outer face of the door and pivotally mounted adjacent the inner face of this off-set portion, upon the pin 8 extending therethrough is a lever 8^a, the mounting point for the lever being intermediate its ends and at one side of the transverse center thereof, as shown.

The inner end of the pin 8 engages in and is

70

supported by the lower portion of the wall 6^c of the roller casing.

To the outer end of each lever 8^a is pivotally attached the upper end portion of a hanger plate 9, the lower edge of which is secured to the door, as indicated at 10. The inner ends of the levers 8^a have attached thereto the control cables 11, which extend downwardly and are secured to a main control lever 12 mounted upon the face of the door beneath a toothed segment 13.

The lever 12 carries a pawl 14, which engages the segment 13, and this pawl is controlled through the medium of a rod 15 connected with a latch 16, pivotally mounted upon the lever adjacent the free end.

From the foregoing description it will be readily seen that vertical shifting of the door 3 is effected by grasping the free end 20 of the main control lever 12, releasing the pawl 14 and pulling down upon the lever, which operation lowers the inner ends of the roller attached levers 8^a, fulcruming each at the point where it is attached to the roller plate and lifting the outer ends and consequently the door. The door can then be readily shifted laterally in the direction desired.

From the foregoing it will be readily seen that with the present device, a door structure 25 may be easily raised or lowered for the performance of the opening operation.

Having thus described my invention, what I claim is:—

1. The combination with a sliding door, of 30 a track secured above the door, encased roller members supported upon said track, hanger plates secured to and extending above the top edge of the door, lever members each pivotally secured inwardly of one end of a roller 40 casing and having the adjacent end pivotally attached to one of said hanger members, and guide bars carried by and suspended from the roller casings, each overlying a face of the door.

2. The combination with a sliding door, of 45 a track secured above the door, encased roller members supported upon said track, hanger plates secured to and extending above the top edge of the door, lever members each pivotally secured inwardly of one end to a roller casing and having the adjacent end pivotally attached to one of said hanger members, a lever member pivotally mounted upon one face of the door, a pawl and segment associated with 50 the lever for holding the same in adjusted position, and connecting elements between said door carried lever and the free ends of the roller carried levers.

3. A sliding door raising and lowering 55 means including a supporting track, comprising a pair of rollers adapted to ride upon said track, a casing for each roller of inverted substantially U-shaped formation, a depending bar having one end turned laterally and attached to one side of each casing, said bar

having a portion in spaced substantially parallel relation with the attached side of the casing, a pin connecting each bar with the adjacent side of the attached casing, a lever oscillatably mounted intermediate its ends upon each pin and having one end adapted to be pivotally attached to the door, and means for actuating the other end of each lever.

In testimony whereof I hereunto affix my signature.

STEPHEN J. JACOBSMEIER.
